UNITED STATES PATENT OFFICE.

DAN GRIFFITH, OF TACOMA, WASHINGTON.

HEATING DEVICE.

1,417,987.

Specification of Letters Patent. Patented May 30, 1922.

Application filed April 19, 1920. Serial No. 375,082.

To all whom it may concern:

Be it known that I, DAN GRIFFITH, a citizen of the United States, and a resident of Tacoma, in the county of Pierce and State 5 of Washington, have invented certain new and useful Improvements in Heating Devices, of which the following is a specification.

My invention is an improvement in heating devices, and has for its object to provide apparatus for use in connection with stoves and the like, for permitting a large amount of the heat usually wasted to be utilized, to heat the room in which the fire is arranged, 10 or to heat other rooms.

In the drawings:

Figure 1 is a sectional view showing the device arranged to heat another room;

Figure 2 is a section on the line 4—4 of 20 Figure 1.

In the embodiment of the invention shown in Figures 1 and 2, the device is shown in connection with a heating stove 13 which has a draft pipe 14 opening into the flue 15. The 25 drum comprises a casing 16 which is arranged within another room, as shown, and this casing has inlet and outlet pipes 17 and 18 which connect the casing with the flue, the inlet pipe being at the bottom of the casing 30 while the outlet pipe 18 is at the top.

A baffle plate 19 is arranged transversely of the casing, the baffle plate at its front edge being spaced apart from the front wall of the casing to provide a passage for the 35 heated gases as shown, and the casing is provided with a door opening 20 below the baffle plate, normally closed by a door 21. This door opening permits the casing to be cleaned when necessary.

A damper 22 is slidably mounted in the 40 pipe 17 to be moved across the flue or to be moved into the pipe 17 where it will not interfere with the passage through the flue, a rod 23 being connected with the damper and having a jointed section 24 at the end remote from the damper.

The rod is slidable through an opening in the casing, and it will be obvious that when the jointed section 24 drops down outside of the casing, as indicated in dotted lines in 50 Figure 3, the damper will be held in the pipe 17. The damper moves in guides 25 in the pipe. With this arrangement, when it is desired to heat the room in which the casing 16 is arranged, the hinged portion 24 of the 55 rod is lifted and the damper is pushed inwardly into position across the flue.

The heated gases now pass from the stove through the draft pipe 14, the flue and the pipe 17 into the casing 16. From here they 60 pass through the pipe 18 and again into the flue. The casing 16 will be heated, thus utilizing the heat which is generally wasted.

I claim:

A heater as herein set forth comprising a 65 casing including front and rear walls, said rear wall provided with openings and upper and lower pipes adapted for connection with a vertical flue, an intermediate baffle plate within the casing extending from the rear 70 wall to near the front wall, guides arranged within the lower pipe within its upper wall, a damper plate of somewhat greater length than the width of the vertical flue slidable in said guides, and a jointed handle attached 75 to the front of said damper plate and extending through the front wall of the casing.

DAN GRIFFITH.
